US00D999879S

(12) **United States Design Patent** (10) **Patent No.:** **US D999,879 S**
(45) **Date of Patent:** **** Sep. 26, 2023**

(54) **FAUCET PULL**

(71) Applicant: **HANSGROHE SE**, Schiltach (DE)

(72) Inventors: **Stefan Hasselwander**, Esslingen (DE);
Andreas Diefenbach,
Ludwigsburg-Ossweil (DE)

(73) Assignee: **Hansgrohe SE**, Schiltach (DE)

(**) Term: **15 Years**

(21) Appl. No.: **29/775,383**

(22) Filed: **Mar. 23, 2021**

(30) **Foreign Application Priority Data**

Oct. 5, 2020 (EM) 008194781-0011

(51) **LOC (14) Cl.** **23-01**

(57) **CLAIM**

The ornamental design for a faucet pull, as shown and described.

DESCRIPTION

FIG. 1 is a perspective view of a faucet pull showing our design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken line disclosures in the view represents portions of a faucet pull in which the claimed design is embodied, but which forms no part of the claimed design.

1 Claim, 7 Drawing Sheets
